UNITED STATES PATENT OFFICE.

MASON H. CRITTENDEN AND FRANK V. EMERY, OF MINNEAPOLIS,
MINNESOTA.

FIREPROOF CONSTRUCTION.

SPECIFICATION forming part of Letters Patent No. 508,501, dated November 14, 1893.

Application filed May 24, 1892. Serial No. 434,221. (No model.)

To all whom it may concern:

Be it known that we, MASON H. CRITTENDEN and FRANK V. EMERY, of the city of Minneapolis, county of Hennepin, and State of Minnesota, have jointly invented certain new and useful Improvements in Fireproof Construction for Plastering, of which the following is a specification.

Our invention relates to fire-proof construction for the interior of buildings whereby metallic lathing suitable for coating with plaster may be conveniently and efficiently supported.

The object of the invention is to provide sheet metal ceiling-joists having means for attaching metallic lathing and adapted to be supported by the feet of metallic floor-joists. This object is accomplished by the construction illustrated in the accompanying drawings in which—

Figure 1 shows a sectional elevation of a portion of a floor, the floor-joists, an arched ceiling, the ceiling-joists and metallic lathing; and Fig. 2 a transverse section of the ceiling-joists on the line $x-x$ of Fig. 1.

In such drawings 1 designates the floor; 2 the floor-joists, and 3 the corrugated arched ceiling of sheet-metal of the usual form having its ends supported by the floor-joists. The space 4 between the arched ceiling and floor

30 may be filled with terra-cotta or other fire-proof material if desired.

The supports for a flat ceiling beneath the floor-joists consist of straight ceiling-joists 5, formed of sheet-metal and preferably made 35 in the following way: Two vertical strips 6 of sheet-metal, having their lower portions bent outward at opposite sides to form flanges 7, are placed together; and around the upward portion of these strips is bent a piece of sheet-

40 metal to form a cap 8 with its lower portions bent laterally to form flanges 9 above the

flanges of the interior strips and the vertical portions 6 and 8 are secured together by rivets 10. A groove or channel 11 is thus made to intervene the two sets of flanges 7 and 9, 45 for receiving the edges of suitable lathing-sheets 12. The lathing-sheets illustrated have longitudinal grooves 13, and the sheets should also be provided between the grooves with some desired form of tongues, loops or other 50 means for locking the plaster. These are not shown in the drawings as they form no part of the present invention.

The ends 14 of the joists 5, are shaped to fit the angular space between the feet of the 55 floor-joists and arched ceiling sheet and are seated on the feet of the floor-joists. These ceiling-joists being placed at proper intervals are adapted to receive the edges of the lathing-sheets in the channels or grooves 11, and 60 to hold them up to a common plane so as to provide a horizontal plastering surface.

Having described our invention, what we claim is—

1. The combination with floor-joists, and an 65 arched ceiling supported thereby, of straight ceiling-joists providing longitudinal grooves to receive the metallic-lathing and having their ends fitting the space between the feet of the floor-joists and arched ceiling, substantially as set forth.

2. The combination with floor-joists having feet; of ceiling joists supported thereon and providing longitudinal grooves for receiving the edges of metallic lathing sheets, substantially as set forth.

MASON H. CRITTENDEN.
FRANK V. EMERY.
